BRACELET OR THE LIKE

Elena Mariani, 377 S. Harrison St.,
East Orange, N.J. 07018

Filed May 15, 1967, Ser. No. 7,374

Term of patent 14 years

(Cl. D45—4)

FIG. 1

FIG. 2

FIG. 3

FIG. 4

FIG. 5

FIG. 1 is a front elevational view of a bracelet or the like showing my new design, said bracelet being constructed from a spirally wound double wire;

FIG. 2 is an edge view thereof;

FIG. 3 is a rear elevational view thereof;

FIG. 4 is a front elevational view of a bracelet or the like showing a modified form of my new design wherein the bracelet is constructed of a single spirally wound wire, the bracelet having the same appearance in rear elevation; and

FIG. 5 is an end elevational view of the bracelet shown in FIG. 4.

The characteristic feature of the instant invention resides in a wire spirally wound so as to form a plurality of loose, resilient, side-by-side convolutions of substantially the same diameter, said convolutions extending substantially tangentially from the inner surface of the bracelet to the outer surface thereof.

This is a continuation-in-part of design application Ser. No. 5,789, filed Feb. 13, 1967, and now abandoned.

I claim:

The ornamental design for a bracelet or the like, substantially as shown and described.
